UNITED STATES PATENT OFFICE

2,500,835

RATCHET WRENCH

John W. Lang, Racine, Wis.

Application February 17, 1947, Serial No. 729,045

3 Claims. (Cl. 81—61)

1

This invention relates to improvements in ratchet wrenches, and in particular to double ended box type ratchet wrenches.

The conventional ratchet type of wrench is usually of relatively complex construction, and the manufacture thereof entails a multiplicity of operations. In the case of those few in which the design is relatively simple, the ratchet mechanism thereof is often subject to rapid wear and frequently becomes inoperative due to failure of the spring therein or due to failure of the dog to positively engage the rotating portion thereof. In certain double ended ratchet wrenches, a single spring actuates the dogs of the ratchet mechanisms on both ends thereof. A failure of this spring renders the mechanisms of both ends of the wrench inoperative. In certain other ratchet wrenches coil springs are used. This type of spring has the undesirable feature of losing its tensile qualities after a comparatively short period of use, thereby resulting in failure of the dog to properly function. Certain other ratchet wrenches employ a spring which is susceptible of displacement and, when such displacement occurs, the result is a failure of the ratchet mechanism.

It is therefore a general object of this invention to provide a ratchet wrench which is simple in design, and which can be fabricated with a minimum of manufacturing operations.

A further object of the invention is to provide a wrench having a ratchet mechanism so constructed that the dog therein is actuated into positive engagement with the rotating portion thereof, said mechanism being so arranged and constructed that it is relatively foolproof.

A further object of the invention is to provide a double ended ratchet wrench having embodied in the mechanism, at each end thereof, an individual flat spring.

A further more specific object of the invention is to provide a ratchet wrench embodying a flat spring which is so constructed and disposed as to prevent its displacement.

A further object of the invention is to provide a ratchet wrench wherein the elongated top and bottom plates are held in properly spaced condition by a spacer bar, said bar having end recesses shaped to receive and position portions of the band springs.

A further object of the invention is to provide a construction as above described, wherein pins or rivets which connect the top and bottom plates are located adjacent the inner ends of the recesses in the spacer bar to not only maintain

2

said bar in proper assembled position, but also to cooperate with the recesses in the bar in maintaining the springs in properly assembled position.

- 5 With the above and other objects in view, the invention consists of the improved ratchet wrench, and all its parts and combinations, as set forth in the claims, and all equivalents thereof.
- 10 In the accompanying drawings illustrating one complete embodiment of the preferred form of the invention, in which the same reference numerals designate the same parts in all of the views:
- 15 Fig. 1 is a plan view of the improved wrench; Fig. 2 is a side view of the improved wrench; Fig. 3 is a plan view of the wrench having the upper side member removed, and before the upper ends of the pins are peened over; and
- 20 Fig. 4 is a vertical cross-sectional view taken along the line 4—4 of Fig. 3.
- Referring more particularly to the drawing, there is an upper side member or elongated plate 5, and a lower side member or elongated plate 6.
- 25 The upper side member 5 is formed with an enlarged portion 7 at one end and with a similarly enlarged portion 8 at the opposite end. The lower side member 6 is formed with an enlarged portion 7' at one end and a similarly enlarged portion 8' at the opposite end. Disposed between the members 5 and 6 is a spacer bar 9 having a V-notch 10 at each end thereof. The apex of each V-notch 10 is preferably rounded as at 11.
- 30 The enlarged portions 7 of the member 5 and the enlarged portions 7' of the member 6 contain identical apertures 12 and 12' respectively. The enlarged portion 8 of the member 5 and the enlarged portion 8' of the member 6 contain identical apertures 13 and 13' respectively.
- 35 Rotatably supported in the apertures 12 and 12' is a sleeve 14, and similarly disposed in apertures 13 and 13' is a sleeve 15. The interiors 16 of the sleeves 14 and 15 are preferably formed with
- 40 what is known as a twelve point construction as is commonly used in box wrenches and socket wrenches. The sleeves 14 and 15 are preferably of different sizes so that the interiors 16 of the respective sleeves 14 and 15 accommodate different sizes of fittings. The sleeves 14 and 15 are each formed with a peripheral shoulder 17 midway between the ends thereof. The shoulders 17 are disposed between those portions of the member 5 which surround the apertures 12 and 13,
- 45 and between those portions of the member 6
- 50

which surround the apertures 12' and 13'. The periphery of each shoulder 17 is formed with spaced transverse ratchet notches 18 preferably having an angularity of approximately 90° between the faces thereof.

Extending transversely between the members 5 and 6 and transversely through the V-notches 10 near the rounded apex portions 11 thereof are pins 19 and 20 connecting the members 5 and 6. The pins 19 and 20 are positioned on the longitudinal axis of the members 5 and 6 and the heads of said pins are formed as rivet heads. Also disposed on the longitudinal axis of the members 5 and 6, and riveting the members 5 and 6 together are pins 21 and 22. Pivottally mounted on the pins 21 and 22 are dogs 23 and 24 respectively. Conforming to the shape of the V-notches 10 and extending around the pins 19 and 20 respectively are J-shaped band springs 25 and 26. The extending portions of the springs 25 and 26 coact with the inwardly projecting portions of the dogs 23 and 24 and force the outwardly projecting portions of the dogs 23 and 24 into engagement with the ratchet notches 18 of the sleeves 14 and 15.

It is apparent from the above description and drawing that the sleeves 14 and 15 will rotate in only one direction, each of the dogs 23 and 24 being forced into positive engagement with one of the notches 18 whenever rotation is stopped. The portions of the dogs 23 and 24 which engage the notches 18 are of such shape that the engaging faces thereof contact substantially the entire face of one side of a notch 18, thereby providing positive action. This engagement becomes more positive as force is exerted in an attempt to rotate the sleeves 14 and 15 toward the dog (counterclockwise in Fig. 3).

The improved wrench is simple in design, the component parts thereof being easily formed and quickly assembled. The springs used are susceptible of neither fatigue nor displacement, but if for some reason one of the springs should fail, the mechanism at the opposite end of the wrench remains entirely operative. The wrench is sturdy of construction, and well adapted to the purposes for which designed. It may be used with either side up, depending upon which direction of rotation is desired.

It is also apparent that the assembly of the improved wrench is very simple and can be performed by relatively inexperienced labor. The pins or rivets 19 and 20 fit at the apexes of the V-recesses 10 and serve not only to connect the top and bottom plates 5 and 6, but also to secure the spacer bar in proper assembled position. In addition, these pins coact with the rounded apexes of the V-recesses 10 to maintain the reversely bent ends of the springs 25 and 26 in assembled position.

While many features of the invention are particularly adapted for use in ratchet wrenches of the double ended type, nevertheless, other features have utility in single ended wrenches and it is therefore contemplated that the invention apply to wrenches of the latter type wherever it is suitable.

Various other changes and modifications may be made without departing from the spirit of the invention, and all of such changes are contemplated, as may come within the scope of the claims.

What I claim is:

1. In a double-ended ratchet wrench having an independent ratchet mechanism at each end thereof, having a bottom plate, and having a top plate, a spacer member between said top and bottom plates and having each end formed with a V-shaped recess adjacent one of said ratchet mechanisms; and a transverse pin extending between said plates and disposed within and adjacent the apex of each of said V-shaped recesses to hold said spacer bar in assembled position, each of said independent ratchet mechanisms including a flat ratchet dog actuating spring having a reversely bent end fitting around the adjacent pin and within the adjacent V-shaped recess and conforming to the surfaces of said pin and said V-shaped recess in contact therewith whereby said spring is held in operative position in said recess by said pin.

2. In a double-ended ratchet wrench having an independent ratchet mechanism at each end thereof, having a bottom plate, and having a top plate, a spacer bar between said top and bottom plates and having each end formed with a V-shaped recess adjacent one of said ratchet mechanisms; and a transverse pin disposed within and adjacent the apex of each of said V-shaped recesses, said pins extending through said plates and maintaining the plates and spacer bar in assembled condition, each of said ratchet mechanisms including a flat ratchet dog actuating spring held in operative position within one of said recesses by one of said pins.

3. In a double-ended ratchet wrench having an independent ratchet mechanism at each end thereof, having a bottom plate, and having a top plate, a spacer member between said top and bottom plates and having each end formed with a V-shaped recess; and a transverse pin disposed within and adjacent the apex of each of said V-shaped recesses and extending through said plates and maintaining the wrench in assembled condition, each of said independent ratchet mechanism including a flat ratchet dog actuating spring having a reversely bent end fitting around the adjacent pin and within the adjacent V-shaped recess and conforming to the surfaces of said pin and said V-shaped recess in contact therewith.
